COMBINED LIGHTER AND CANE

Filed Jan. 20, 1928

INVENTOR,
Aniceto R. Visitacion
BY,
Warren E. Willis,
ATTORNEY.

UNITED STATES PATENT OFFICE.

ANICETO R. VISITACION, OF NEW YORK, N. Y., ASSIGNOR OF ONE-FOURTH TO GENERAL WILLIAM WEIGEL AND ONE-HALF TO LOUIS G. WEIGEL, BOTH OF NEW YORK, N. Y.

COMBINED LIGHTER AND CANE.

Application filed January 20, 1928. Serial No. 248,098.

This invention relates to lighters, as used in igniting cigars and cigarettes, in combination with hand carried articles of the cane type as exemplified by swagger sticks, umbrella handles and the like.

The ordinary pocket carried lighter has certain disadvantages among which is the space occupied in a pocket, its liability to become lost, stolen or mislaid, the possibility of its fluid container leaking causing damage to the clothing in which it is carried, and the further well known difficulty in obtaining a light when in a strong wind or stormy weather.

15 The prevailing fashion of carrying a cane and the almost universal custom of using an umbrella in inclement weather is well known.

It is therefore an object of the present 20 invention to provide a lighter incorporated within a stick, which term is to be understood as generic rather than specific, thereby relieving the pocket of bulk and weight and the garments from drippings and odor.

25 A further feature is to so combine the lighter that the stick is strengthened and reinforced rather than weakened and its appearance materially enhanced and improved.

30 Another purpose is to produce a lighter so arranged within the body of a stick as to be sheltered and protected, thereby being usable in any kind of weather free from the effects of wind or rain, and by which a cigar 35 or the like may be lit under the most disadvantageous circumstances.

These and other important features, that will more fully hereinafter appear, are accomplished by the novel construction, arrangement and combination of parts herein- 40 after described and illustrated in the accompanying drawing, forming a material part of this disclosure, and in which:—

Figure 1 is a side elevational view of a 45 conventional type of cane showing an embodiment of the invention as combined therein.

Figure 2 is a fragmentary longitudinal 50 sectional view of the stick with the lighter carried thereon and drawn to a greatly enlarged scale.

Figure 3 is a side elevational view of the

same, parts being broken away to disclose the construction, the device being shown in open operative position.

55

Figure 4 is a transverse sectional view taken in a plane indicated by the line 4—4 of Figure 2.

The cane or walking stick shown in Figure 1 is composed of the usual main staff 60 portion 10, having a ferrule 11, crooked handle 12 and tip 13.

In the present instance the staff 10 and handle 12, which may be of wood as usual, have between them a tube 14 which may be 65 so blended as to be substantially indistinguishable.

The lower end 15 of the handle 12 is preferably reduced in diameter and tight fitted to an inverted cap 16 made of metal, the cap 70 being set in the upper end of the tube 14 and firmly held by a pin 17 passing through the several parts and riveted at its ends to retain the tube and handle as a unit.

The lower end of the tube 14 is screw- 75 threaded interiorly to engage the periphery of an annular block 18 seated on the upper end of the staff 10 which contains an axial opening to receive a hollow boss 19 extending integrally from the block and carrying 80 a screw 20 set in the staff as shown in Figure 2, thereby holding the block rigidly to the staff, the block being prevented from turning by spurs 21 on its lower side projecting into the wood.

85 The block 18 contains a recess 22 in its upper side and its edge is adapted to clamp a plate 23 between it and a shoulder 24 of the tube, this plate being the bottom member of a cylindrical container 25 freely fitting 90 the tube and acting as a reservoir for a fluid used to saturate a wick 26 disposed in a wick tube 27 extending down into the container whereby a flame 28 may be produced.

Carried on top of the container, through 95 which the wick tube extends, and adjacent to it, is a forked support 29, between the prongs of which is a sharply corrugated wheel 30 revoluble on a pin 31 fixed in the forks.

100 Below the wheel 30 is a stick of pyrophoric material 32, carried in a tube extending into the reservoir 25 and spring pressed against the wheel in the usual manner.

The tube 14 has a straight inreaching cut 33 in the side adjacent the abrading wheel, extending transversely from a point about level with its periphery to the center of the tube, this cut intersecting with an angular cut 34 reaching to a point level with the bottom of the cap 16, thus presenting a substantially triangular opening.

A cover 35 is fitted to this opening and held by a hinge 36 at its lower edge, the hinge pin being encircled by a spring 37, the ends of the spring being disposed in such manner as to throw the cover outwardly into the angular position shown in Figure 3 when 10 the cover is released, but prevents actual contact of the back of the cover with the tube wall.

The ferrule 11 is slidable on the tube 14 and adjacent portion of the handle 12, its 20 normal position being downward and limited by the hinge 36, as seen in Figures 1 and 2, the ferrule in that position overlying the cover 35 and completely obscuring it from view, but upon raising the ferrule, as shown 25 in Figure 3, the cover will be thrust open by the spring 37.

Carried on the inner side of the cover 35 is a bracket 38, in which, pivoted on a pin 39 is an arcuate arm 40 serrated on its inner 30 surface 41 and adapted to engage the wheel 30 and cause it to rotate when the cover is moved outwardly, a spring 42 encircling the pin 39 having its ends arranged to press the arm 40 into operative position.

The arm 40 is provided with a snuffer cap 43 adapted to engage over the wick tube 27 when the cover is in a closed position, effectively preventing leakage and protecting the wick, the cap 43 rising so as not to interfere 40 with the passage of sparks from the wheel 30 to the wick as the cover moves outwardly.

The position of a cigarette or cigar when being lit is indicated at 44, showing it as entered into the triangular opening in the tube 14 close to the flame 28 which is fully 45 protected from rain and wind and also from injuring the handle due to the metal cap 16.

The sparking material may be adjusted towards the wheel by turning the screw 45, 50 shown as projecting into the block recess 22 and the fuel container is easily removed for refilling by unscrewing the tube 14 from the block 18.

The foregoing disclosure is to be regarded 55 as descriptive and illustrative only, and not as restrictive or limitative of the invention, of which obviously an embodiment may be constructed including many modifications without departing from the general scope 60 herein indicated and denoted in the appended claims.

Having thus described my invention, what I claim as new and desire to secure by Letters Patent, is:—

1. The combination with an object having

two spaced apart portions, of a tube connecting therebetween, said tube having an opening in one side, a cover hinged to the tube to engage in said opening, a lighter carried in said tube, and means carried by said cover 70 to operate the lighter.

2. A cylindrical tube having an opening in its side wall, a cover hinged to close the opening, a spring urging said cover outwardly, a ferrule slidable on said tube to engage over said cover, a lighter in the tube, and means carried by said cover to cause ignition of the lighter when the cover is released. 75

3. A cylinder composed of two solid sections, and an intermediate hollow section therebetween, said hollow section having a lateral opening and a closure therefor, a ferrule slidable on the hollow section to envelop the closure, a lighter disposed in the 85 hollow section, and means on said closure to actuate said lighter whereby a flame is produced said flame being accessible through said opening. 80

4. A device composed of two solid cylindrical sections, and an intermediate hollow section therebetween, said hollow section having a lateral opening and a closure therefor, a ferrule slidable on the hollow section to envelop the closure, a lighter disposed in the 95 hollow section, said lighter including a fuel reservoir, a wick carrying tube, and a sparking means, an arcuate arm pivoted to said closure, resilient means to press said arm into operative engagement with the 100 sparking means when said closure is released by the ferrule, and means for moving said closure outwardly upon its release.

5. A device composed of two solid cylindrical sections respectively upper and lower, a metal cap on the inner end of the upper section, a block fixed on the inner end of the lower section, a tube registering with both sections and connecting therebetween, said tube being rigidly engaged over said 105 cap to the upper section and removably engaged over said block, a pyrophoric lighter carried in said tube adjacent the lower section, there being a chamber thereabove having a lateral opening below said cap, a cover hinged to said tube to close the opening, a ferrule slidable over said tube and inner end of said upper section, said ferrule being disposable over said cover and limited in movement by the hinge thereof, a spring pressed 110 arm on said cover operatively engageable with the lighter, and means carried by said arm to extinguish the lighter when said cover is closed. 115

6. A lighter comprising a tube, said tube being partially open at one side, a cover hinged thereto, a spring for throwing said cover to its open position, a ferrule to hold said cover closed, means connected to the cover to operate the sparking means when 120 125 130

the cover is thrown to its open position, and means to prevent over actuation of said cover.

7. A cigar lighter comprising a tube having a lateral opening, a container for liquid fuel set in one end of said tube, a casing in said container for pyrophoric material, a wick tube in said container its outer end

being contiguous to the material tube, an abrading wheel over the material tube, a cover for the opening in said tube, an arm to actuate said wheel when said cover is thrown open, and means to retain said cover in a normally closed position.

In testimony whereof I affix my signature.
ANICETO R. VISITACION.
